(57) **CLAIM**

The ornamental design for a foldable table and frame, as shown and described.

DESCRIPTION

FIG. 1 is a perspective view of an embodiment of the foldable table frame in a folded configuration;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of the foldable table frame in an unfolded configuration;

FIG. 9 is a front view thereof;

FIG. 10 is a rear view thereof;

FIG. 11 is right side view thereof;

FIG. 12 is a left side view thereof;

FIG. 13 is a top plan view thereof;

FIG. 14 is a bottom plan view thereof;

FIG. 15 is a perspective view of an alternate embodiment of the foldable table frame in a folded configuration;

FIG. 16 is a front view thereof;

FIG. 17 is a rear view thereof;

FIG. 18 is right side view thereof;

FIG. 19 is a left side view thereof;

FIG. 20 is a top plan view thereof;

FIG. 21 is a bottom plan view thereof;

FIG. 22 is a perspective view of the foldable table frame in an unfolded configuration;

FIG. 23 is a front view thereof;

FIG. 24 is a rear view thereof;

FIG. 25 is right side view thereof;

FIG. 26 is a left side view thereof;

FIG. 27 is a top plan view thereof; and,

FIG. 28 is a bottom plan view thereof.
